MACHINE FOR REMOVING SHOES
FROM LASTSCharles Cushman Abbot, Auburn, and Leo A.
Gilbert, Lewiston, Maine

Application March 29, 1934, Serial No. 717,900

4 Claims. (Cl. 12—15.1)

This invention relates to the manufacture of boots and shoes and its purpose specifically is to remove a shoe from the last on which it has been built up.

In the process of making shoes, a last is supported upside down on a pedestal while the sole and upper are being worked on and at the proper time when the process is finished, the shoe must be removed from the last to make place for another. This has generally been accomplished by hand and requires considerable strength.

The purpose of this machine is to remove the shoe from the last, to loosen the heel part from the heel part of the last and to apply the necessary force or pressure at exactly the right place and in exactly the right way to get the best and quickest results, and preferably by the application of foot power instead of hand power.

In the drawing, Fig. 1 is a side elevation of the machine with the moving parts stationary in their usual position and with a shoe in its usual position on a last.

Fig. 2 is a side elevation of the same machine with the foot of the operator applied to the treadle sufficiently to bring the friction pad in contact with the shoe heel.

Fig. 3 shows the last or finishing position of the foot treadle, friction pad and of the shoe heel when released from the last.

Fig. 4 shows in detail the position of the cam roller and end cam when at rest and at the end of the movement, the relative movement being exaggerated for clearness.

Fig. 5 is an isometric view of the rubber pad.

Fig. 6 is a plan view of the push rod guide.

In the drawing, P represents a pedestal at the top of which is a pin 9 to which a last such as L is fastened upside down so as to receive a shoe S while it is being worked on or made.

T is a foot treadle medially pivoted to the pedestal P at 10 and having at one end a foot rest 11 and preferably at the other end a counter-weight 12 to bring it back to the down position when the foot F of the operator is removed. This counter-weight 12 may also if desired be used as a stop to prevent the bottom of push rod R from slipping off cam roller 13 which is in position on treadle T close to 12 and which engages the slantingly cut end 3 of the bottom of push rod R. This part 3 is substantially an end cam.

Positioned part way up the pedestal P is a push rod guide G in which is a guide slot 20 at the outer end of which is preferably a guide roller 25 and at the inner end a guide finger 26

which is slidable and normally pressed outward by a compression spring 27.

Push rod R passes through this guide slot 20 between roller 25 and finger 26 and when at rest is hung on guide G by means of a floating pivot pin or support 1 which extends through and across rod R and rests upon the flat top surface 21 of guide G.

Preferably the guide G is horizontally slideable in the holes or bearings 22 and 23 in pedestal P and it, with slot 20, can be adjusted and held nearer to or farther away from pedestal P as desired. This permits adjustment for different sizes of shoes and lasts.

Preferably slot 20 is nearer pedestal P than the cam roller 13 so that when the foot F is removed from rest 11 the counter-weight 12 drops roller 13 and the lower part of rod R which is preferably heavier than the top part causes the lower part to swing towards pedestal P and the top part away from it.

The force of gravity and the positions of the guide 26 and roller 25 which are the ends of slot 20, the position of guide G, pin 1 and if necessary the member 12 locate push rod R as desired.

At the upper end of rod R is fixed a friction pad 2 preferably of rubber or some similar friction material of a size and shape to produce frictional pressure on the heel part 4 of a shoe S when it comes in contact therewith.

The bottom of rod R is cut on a slant or is formed as an end cam 3 which normally, with the parts at rest, rests on the cam roller 13.

The tail or stop 5 extends down below the part 3 and prevents the cam roller 13 from slipping out from under cam 3. The shape of the part 3 determines to a great extent the movement of rod R and pad 2.

The action is as follows:

Fig. 1 shows the parts in normal or inactive position.

As shown in Fig. 2 when the operator wishes to remove the shoe S from the last L, he places his foot F on rest 11 of treadle T and bears his weight on it. This action, of course, lifts the roller 13 and its first action on end cam 3 is to force it away from pedestal P, rod R pivoting on pin 1 and on guide roller 25 until pad 2 is moved over into contact with the heel part 4 of shoe S and is stopped there because the last L will not move.

As the pressure or weight continues to be applied through foot F, rod R cannot continue to rock, but roller 13 acting on the part 3 forces

the rod against roller 25 and upward, the composition of forces being such that the friction pad 2 is not only pressed with great force against the heel part 4 of the shoe S, but is also forced upward, as shown in Figs. 3 and 4, carrying with it heel 4 which slips along the heel 14 of the last thus freeing the shoe from the last.

As the outside end of slot 20 where roller 25 is located is nearer to the pedestal P than the roller 13, as roller 13 rises it moves the pad 2 toward the pedestal and at the same time forces guide G away from the pedestal as far as nut 28 will permit.

The guide roller 25 and finger 26 in slot 20 might be omitted and instead of a cam roller 13, any kind of a member which would slide against the cam 3, and which could be raised and lowered, might be used.

I claim:

20. 1. In a machine for removing shoes from lasts; the combination of a pedestal having at its top means for supporting a last upside down; with a foot treadle medially pivoted to the pedestal and having a foot rest at one end and a counter-weight stop and a cam roller at the other end; an adjustable push rod guide through which is a push rod guide slot in which is a guide roller and a guide finger; and a push rod which passes through the guide slot between the guide roller and the guide finger and is normally supported by a floating pivot pin which rests on the push rod guide, there being a friction pad at the top end of the push rod and, at the bottom end, an end cam in engagement with the cam roller.
25. 2. In a machine for removing shoes from lasts; the combination of a pedestal having at its top means for supporting a last upside down; with a push rod guide which extends out medially of the pedestal and has a push rod guide slot; a push rod which passes through the guide slot and is normally supported by a floating pivot pin which rests on the top of the push rod guide,
30. 3. In a machine for removing shoes from lasts; the combination of a pedestal having at its top means for supporting a last upside down; with a push rod guide which extends out medially of the pedestal and has a push rod guide slot; a push rod which passes through the guide slot and is normally supported by a floating pivot pin which rests on the top of the push rod guide,
35. 4. In a machine for removing shoes from lasts; the combination of a pedestal having at its top means for supporting a last upside down; with a push rod guide which extends out medially of the pedestal and has a push rod guide slot; a push rod which passes through the guide slot and is normally supported by a floating pivot pin which rests on the top of the push rod guide,
40. 5. In a machine for removing shoes from lasts; the combination of a pedestal having at its top means for supporting a last upside down; with a push rod guide which extends out medially of the pedestal and has a push rod guide slot; a push rod which passes through the guide slot and is normally supported by a floating pivot pin which rests on the top of the push rod guide,

said push rod having a friction pad at its top end and, at its bottom end, an end cam; and a member on which the end cam slidably rests, which member can be raised and lowered.

3. In a machine for removing shoes from lasts; the combination of a pedestal having at its top means for supporting a last upside down; with a foot treadle medially pivoted to the pedestal and having a foot rest at one end and a counter-weight stop and a cam roller at the other end; an adjustable push rod guide through which is a push rod guide slot in which is a guide roller and a guide finger; and a push rod which passes through the guide slot between the guide roller and the guide finger and is normally supported by a floating pivot pin which rests on the push rod guide, there being a friction pad at the top end of the push rod and, at the bottom end, an end cam in engagement with the cam roller, such end cam being so cut that the upward movement of the roller will rock the push rod until the pad strikes the last and will then be forced upward in engagement with the last.

4. In a machine for removing shoes from lasts; the combination of a pedestal having at its top means for supporting a last upside down; with a push rod guide which extends out medially of the pedestal and has a push rod guide slot; a push rod which passes through the guide slot and is normally supported by a floating pivot pin which rests on the top of the push rod guide, said push rod having a friction pad at its top end and, at its bottom end, an end cam; and a member on which the end cam slidably rests, which member can be raised and lowered, such end cam being so cut that the upward movement of the member on which it rests will rock the push rod until the pad strikes the last and will then be forced upward in engagement with the last.
